United States Patent Office

Des. 199,179
Patented Sept. 22, 1964

199,179

STOVE MAT

Meyer Steinberg, Woodmere, N.Y. (½ Ideal Rubber
Products Co., 273-299 Van Sinderen Ave., Brooklyn 7,
N.Y.)

Filed July 2, 1962, Ser. No. 70,757

Term of patent 14 years

(Cl. D9—6)

FIG. 1.

FIG. 3.

FIG. 2.

FIG. 4.

Fig. 5.

FIG. 1 is a top plan view of a stove mat, embodying my new design;

FIG. 2 is an enlarged top plan detail view of the upper left quarter thereof;

FIG. 3 is an enlarged section detail view taken on the line 3—3 of FIG. 2;

FIG. 4 is an enlarged section detail view taken on the line 4—4 of FIG. 2;

FIG. 5 is a bottom plan view thereof.

I claim:

The ornamental design for a stove mat, substantially as shown.
